HOUSING FOR LAPIDARY EQUIPMENT

Emmett Stephenson, 6609 Elm, and Vincent A. Coddington, 7344 College, both of Kansas City, Mo.

Filed Sept. 8, 1964, Ser. No. 81,640

Term of patent 14 years

(Cl. D37—1)

Fig.1.

Fig.2.

Fig.3.

FIG. 1 is a perspective view of a housing for lapidary equipment, showing our new design;

FIG. 2 is an elevational view of the end thereof opposite to that shown in FIG. 1; and

FIG. 3 is a rear elevational view thereof.

The dominant features of our design reside in the portions shown in full lines.

We claim:

The ornamental design for a housing for lapidary equipment, as shown and described.

No references cited.

WALLACE R. BURKE, Acting Primary Examiner.
